UNITED STATES PATENT OFFICE.

ELMER V. SMITH, OF BOZEMAN, MONTANA, ASSIGNOR OF FIFTY-ONE ONE-HUNDREDTH TO JOHN J. WHITE, OF BOZEMAN, MONTANA.

STREET-LIGHTING LAMP.

1,201,108.

Specification of Letters Patent. Patented Oct. 10, 1916.

Application filed February 28, 1916. Serial No. 80,986.

To all whom it may concern:

Be it known that I, ELMER V. SMITH, a citizen of the United States, residing at Bozeman, in the county of Gallatin and State of Montana, have invented certain new and useful Improvements in Street-Lighting Lamps; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to street illuminating lamps of the series or multiple type and it has for its object to provide a lamp of simple construction which will distribute the light ray downwardly and laterally as far as the efficiency of the light unit will permit.

A further object is to provide a direct street lighting lamp, which will reflect the rays which are ordinarily wasted in the sky together with other rays, downwardly and laterally, through prism glasses which will distribute said rays in such a manner as to prevent any shadows being cast by the frame supporting said lamp and said rays being distributed uniformly to prevent the usual bright spot at the base of the supporting lamp post.

These as well as other objects, which will readily appear to those skilled in the art, I attain in the device described in the specification and illustrated in the accompanying drawings forming a part of this application, and in which:—

Figure 1 is a side elevation of a lamp constructed in accordance with my invention. Fig. 2 is a vertical section, and Fig. 3 is a section on line 3—3 of Fig. 2.

Reference now being had to the details of the drawings by letter, A represents a supporting post of suitable construction, to the top of which is secured my improved street lighting lamp, which comprises a frame A' having a band A² and lower band A³. Said lower band is so shaped as to conform to and snugly fit the upper end of the post A, and

extending upwardly and inwardly from said band A² are straps A⁴ which are adapted to be clamped to the upper end of the post A by a nut and washer A⁵ carried by a rod B, secured within the post by means not shown. 55

Extending upward from the band A² and connected to the upper band A² are ribs C, which are provided with guideways C' to receive the prism glasses D, said glasses being set at a slight angle as shown. Secured 60 to the upper end A² by lugs A⁶ and screws A⁷ is a light ray reflecting top D', preferably hexagonal in plan and pyramidal in cross section and secured to the under side of said top and near the apex thereof is a convexed 65 reflector D², the object of which is to reflect those light rays from the lighting unit E (which would be wasted in the apex of the top D') back to the prism glasses to be distributed therefrom, thereby utilizing the full 70 efficiency of the lighting unit.

What I claim to be new is:—

1. A supporting post, a lamp thereon, a lower band conforming to and snugly fitting the upper end of said post, straps extending upwardly from said band, an upper band, a light ray reflecting top secured to the upper band, a convexed reflector suspended within said top, ribs connecting the upper and lower bands and prism glasses supported by said ribs and coöperating with said reflector. 75

2. A supporting post, a lamp thereon, a lower band conforming to and snugly fitting the upper end of said post, straps extending upwardly from said band, an upper band, a light ray reflecting top secured to the upper band, a convexed reflector suspended within said top, ribs connecting the upper and lower bands, prism glasses supported by said ribs and coöperating with said reflector, and means for supporting an electric lamp beneath said reflector. 85

In testimony whereof I hereunto affix my signature in presence of two witnesses.

ELMER V. SMITH.
